Assignor to
The Lowell Manufacturing Company.
Letters Patent No. 1556, dated Mar. 25, 1862.

The schedule referred to in these Letters Patent and making part of the same.

To all whom it may concern:

Be it known that I, Elimir J. Ney, of Lowell,

Dec. 1556

in the County of Middlesex, and State of Massachusetts, have originated and designed a new Pattern for Carpets or other fabrics, of which the following is a full, clear and exact description, reference being had to the accompanying drawings, making part of this specification.

In Corner A. is one fourth of a rosette resting on a ground of small diamonds. This ground is surrounded successively by the band 1, scalloped work 2, mottled work 3, band 4, and sprig work 5.

In Corner B. is one fourth of a large block, which is divided into small squares by rows of balls running at right angles with each other. The frame 6, surrounds the blocks before mentioned.

C. at the sides is a scroll figure surrounded by branches of leaves which meet on the ground 7. When the design is matched, a broad belt, composed of a chain of leaves and flowers with a scalloped band on one side and lace work on the other, winds continuously through the design and surrounds the ground 7.

One section of this belt, D. D. in the drawing, overlaps a portion of the frame 6; also portions of the mottled work 3, band 4, and sprig work 5.

Another section, E. E. in the drawing, overlaps a part of the frame 6, and sprig work 5.

This section also underlies a portion of the section D. D.

In corners 8, and 9, are irregular veined leaves.

The colors employed for the different portions of the design, may be varied to suit the taste and wish of the manufacturer.

Claim.

What I claim as my invention and desire to secure by Letters Patent, is the design or pattern, for carpets or other fabrics, herein set forth.

Witnesses.
